UNITED STATES PATENT OFFICE.

JEPTHAH G. DUNLAP, OF CEDARVILLE, OHIO.

BREECH-LOADING FIRE-ARM.

SPECIFICATION forming part of Letters Patent No. 236,791, dated January 18, 1881.

Application filed May 22, 1880. (No model.)

To all whom it may concern:

Be it known that I, JEPTHAH GARRARD DUNLAP, of Cedarville, in the county of Greene and State of Ohio, have invented a new and 5 useful Improvement in Breech-Loading Fire- Arms, of which the following is a specification.

My invention relates to that class of fire- arms in which the barrel tilts up at the breech.

10 The invention consists in a novel construc- tion, arrangement, and operation of a bolt for locking the barrel in place when the breech is closed and devices for operating said bolt, and in means for preventing the accidental 15 discharge of the gun before the barrel is locked in place, and also the accidental unshipping of the barrel from the stock, as hereinafter more particularly described.

In the accompanying drawings, Figure 1 is 20 a longitudinal vertical section of the gun with the barrel tilted up at the breech. Fig. 2 is a longitudinal horizontal section taken in the line $\alpha\alpha$ of Fig. 1. Fig. 3 is a detail view of a modification.

25 Similar letters of reference indicate corresponding parts.

A represents the stock, the front end of which is provided with a pivot, B, for the engagement of a hook, C, on the lower side of 30 the breech of the barrel D, by which means the barrel is attached to the stock, so as to allow it to tilt up at the breech.

On the under side of the breech are two 35 catches, E E², which fit nicely in mortises f f² in the bottom of the frame of the stock. The catch E² also passes through a slot, g², in a bolt, G, which slides longitudinally in grooves in the sides of the frame of the stock in a di- 40 rection parallel with the length of the stock and barrel. The longitudinal movement of the bolt G is accomplished by an arm, H, the lower end of which is secured by a screw, h, in a slot, i, in the front end of the trigger- 45 guard J. The rear end of said guard is secured to the stock by screws, and its front end is free to rise and fall in a recess in the stock, the guard itself being elastic. The arm H, from the point where it is pivoted in the slot i, extends upward and forward diagonally, 50 and thence upward and rearward diagonally, as shown in Fig. 1, so that an upward pressure

on the trigger-guard J will give an upward and backward motion to the extreme upper portion of the arm and an oscillating backward motion to the intermediate portion. The ex- 55 treme upper portion works in and is guided by a recess, a², in the side of the frame of the stock. If preferred, however, the arm may be guided and its motion limited by means of a screw, a³, passing transversely through the stock and 60 through a slot in the arm. In some cases one of the screws of the lock-plate may be used for this purpose. The intermediate or forward diagonal portion of the arm H works in a slot, g³, in the bolt G, between two screws, g⁴ g⁵, 65 passing transversely through said bolt, one in front and the other in rear of the arm H.

When the barrel is in place for use the catches E E² are engaged by the bolt G and securely locked. By pressing upward on the 70 trigger-guard J the arm H moves the bolt G backward, so as to disengage it from the catches E E² and allow the barrel to be tilted up at the breech. By pressing downward on the breech the barrel is returned to its place, 75 and the bolt G is caused, by the elasticity of the trigger-guard, to again engage with the catches E E² and lock the barrel in place. The catch E has on its forward lower corner a lug, e, which engages with a bridge, f³, at 80 the top of the mortise f, while the rear lower corner of said catch is engaged by the front end of the bolt G, by which means the accidental unshipping of the barrel is prevented. When it is desired to unship the barrel the 85 guard J is pressed so as to move the bolt G still farther back. Then by sliding the barrel slightly backward the hook C may be disengaged and the barrel unshipped.

For holding the trigger so as to prevent the 90 accidental discharge of the gun when the breech is not closed, two methods may be employed, both of which are shown in Fig. 1. The trigger L is provided with an arm, l, which engages with a shoulder, i², on the trigger- 95 guard J when said guard is pressed upward, so as to prevent the trigger from being pulled. The trigger M is so arranged that its lower end will engage with a recess, i³, in the guard J when said guard is pressed upward, and 100 thus prevent said trigger from being pulled.

When it is desired to oil the bolt G and arm

H without removing the lock-plate or the trigger-guard the screws a^3 , g^5 , and h may be removed. The arm H can then be taken out and oiled, and some oil can be dropped in 5 through the slot i , so as to reach the bolt G.

Fig. 3 illustrates a mode of applying the arm H to a bolt arranged higher than the bolt G above described. The arm H is bent forward again above the rear diagonal portion, 10 and then upward, so as to engage with a bolt, G^2 , arranged to engage with a recess in the breech instead of with the catches E E².

Having thus fully described my invention, I claim as new and desire to secure by Letters Patent—

1. The combination, with an elastic guard, J, of an arm, H, having the form shown, made

fast at the lower end to said guard, and working by means of a slot over the screw a^3 and in a slot of the bolt G, as and for the purpose specified. 20

2. The combination of the trigger L, provided with the arm l, and the trigger-guard J, provided with the shoulder i^2 , as shown and described, for the purpose specified. 25

3. The combination of the trigger M and the trigger-guard J, provided with the recess i^3 , as shown and described, for the purpose specified.

JEPTHAH G. DUNLAP.
